Primary Examiner — Michelle E. Wilson*Assistant Examiner* — Caitlin A Laverty(74) Attorney, Agent, or Firm — Workman Nydegger(57) CLAIM

The ornamental design for a belt bag, as shown and described.

DESCRIPTION

FIG. 1 is a bottom, left, front facing perspective view of our new design for a belt bag;

FIG. 2 is a top, right, rear perspective view thereof;

FIG. 3 is a front facing view thereof;

FIG. 4 is a rear view thereof;

FIG. 5 is a bottom, plan view thereof;

FIG. 6 is a top, plan view thereof;

FIG. 7 is a right side view thereof; and,

FIG. 8 is a left side view thereof.

In the drawings, the broken lines show portions of the belt bag that form no part of the claim.

1 Claim, 5 Drawing Sheets(56)
